CLAIM

The ornamental design for a cutting plotter, as shown and described.

DESCRIPTION

FIG. 1 is a perspective view of a cutting plotter, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the cutting plotter that form part of the claimed design.

The “coolinbo” lettering and icon forming part of the disclosure is a registered trademark of Ghenzhen Duoduo Intelligent Equipment Technology Co., Ltd.

1 Claim, 7 Drawing Sheets
